STEREOPHONIC SOUND PROPAGATION SYSTEM

Sidney E. Levy, White Plains, N.Y., assignor, by direct and mesne assignments, to University Loudspeakers, Inc., White Plains, N.Y., a corporation of New York

Application July 28, 1958, Serial No. 751,557

19 Claims. (Cl. 179—1)

This invention relates to sound reproduction and more particularly to a stereophonic sound propagation system primarily designed for use in the home, but also usable in other appropriate locations.

The basic principles of stereophonic sound propagation have been known for many years, but until the advent of the dual track magnetic tape recorder, the provision of stereophonic sound in the home was not considered practical. Such tape recorders immediately provided the possibility of high quality stereophonic recordings which provide a convenient source of program material, it then only being necessary to provide suitable electronic equipment, including audio amplifiers and a suitable loudspeaker system in order to provide acceptable stereophonic sound in the home which represents a very marked improvement over the old and conventional methods of sound reproduction. There have also recently become commercially available stereophonic disk recordings which may likewise be utilized with the same electronic equipment as is used with magnetic tape recorders and consequently there is now adequate provisions for sources of program material and the main problems reside in the design and installation of the electronic and loudspeaker equipment in the location to be utilized. It is also to be noted that stereophonic program material is now occasionally available by means of radio broadcasts utilizing both AM and FM with the result that AM and FM receivers would supply the program material, rather than tape and disk recordings.

In the installation and design of stereophonic sound propagation systems, many facts and problems must be taken into consideration and since the design and construction of audio amplifiers has now reached a high state of perfection, the primary concern is with the design and installation of proper loudspeaker equipment. In a stereophonic sound propagation system, the sound must emanate from at least two spaced points and this fact immediately introduces the question of size of the installation as well as the shape and size of the room in which the equipment is to be installed and furthermore, since high quality loudspeakers are relatively costly, the number of such speakers must be kept to a minimum consistent with providing the sound quality desired.

Heretofore, it has been usually customary to utilize either a full frequency range loudspeaker at each loudspeaker location or to utilize a multi-speaker array at each location and both of these arrangements are relatively costly in that, full frequency range loudspeakers are expensive and the multispeakers arrays are appreciably more costly and, of course, there is always the problem of providing suitable enclosures or baffles for the speakers or speaker systems or arrays and where good low frequency response is desired from both speaker locations this necessitates relatively large speaker enclosures for baffles at each location.

Heretofore, no particular advantage has been taken of the fact that low frequency sound waves are substantially nondirective, that is to say, a listener cannot easily de-

termine the point from which low frequency sound waves emanate, whereas middle and high frequency sound waves are highly directive and a listener may immediately differentiate between the points from which middle and high frequency sound waves may be emanating. As a result of this fact, it has been found possible to provide a perfectly suitable stereophonic sound propagation system in which the low frequency sound waves emanate from only one point, while the middle and high frequency sound waves emanate from one or more points spaced from the low frequency loudspeaker and it has been found that this provides highly satisfactory stereophonic sound propagation and at the same time, permits a material reduction in size of the installation, particularly the loudspeaker enclosures and consequently there is a material reduction in cost.

It is accordingly an object of the invention to provide a stereophonic sound propagation system utilizing any suitable source of program material and which may be designed to operate satisfactorily in substantially any room or other desired location.

A further object of the invention is the provision of a stereophonic sound propagation system having full frequency range capabilities but utilizing only two loudspeakers disposed in spaced relationship.

A still further object of the invention is the provision of a stereophonic sound propagation system utilizing one full frequency range loudspeaker having two separate voice coils with one voice coil serving to reproduce the full frequency output of one program material source and the other voice coil reproducing only the low frequency output of a second program material source and a second loudspeaker reproducing only the middle and high frequency output of the second program material source.

Another object of the invention is the provision of a stereophonic sound propagation system utilizing a low frequency range loudspeaker having two separate voice coils with one voice coil connected to one source of program material and the other voice coil connected to the other source of program material, both of these connections being through low-pass filters to limit the input to both voice coils to the lower frequencies and a middle and high frequency range loudspeaker disposed on each side of the low frequency speaker, one of the high frequency speakers being connected to one program material source through a high-pass filter and the other high frequency speaker being connected to the second program material source through a high-pass filter.

A further object of the invention is the provision of a stereophonic sound propagation system utilizing a full frequency range loudspeaker having two separate voice coils with one voice coil connected to the output of one program material source and the other voice coil connected to the output of a second program source to reproduce the full frequency output of both program material sources, a middle and high frequency range loudspeaker connected to the output of one program material source through a high-pass filter and a second middle and high frequency range loudspeaker connected to the second program material source through a high-pass filter with the two high frequencies speakers reproducing only the middle and high frequency outputs of the two program material sources.

A still further object of the invention is the provision of a stereophonic sound propagation system utilizing a loudspeaker having two separate voice coils, one voice coil being connected to one program material source and the other voice coil being connected to a second program material source and at least one middle and high frequency range loudspeaker connected through a high-pass filter to the output of either of the program material sources.

Another object of the invention is the provision of a stereophonic sound propagation system utilizing a plurality of loudspeakers disposed in spaced relation and in which a volume level control is provided for each loudspeaker in order to provide a proper balance between the outputs of the various speakers.

Further objects and advantages of the invention will be apparent from the following description taken in conjunction with the accompanying drawing wherein:

Fig. 1 is a diagrammatic view showing a stereophonic sound propagation system constructed in accordance with this invention and utilizing one full frequency range loudspeaker having two separate voice coils and one middle and high frequency range loudspeaker;

Fig. 2 a diagrammatic view showing a further form of the stereophonic sound propagation system of this invention and utilizing a low frequency range loudspeaker with two separate voice coils and two middle and high frequency range loudspeakers; and

Fig. 3 a view similar to Fig. 2, but showing a further modified form of the invention utilizing a full frequency range loudspeaker having two separate voice coils and two middle and high frequency range loudspeakers.

With continued reference to the drawing and particularly Fig. 1, there is shown a stereophonic sound propagation system constructed in accordance with this invention and which may well comprise two sources of program material indicated in the drawing as amplifier A and amplifier B. While these sources are indicated as audio amplifiers, obviously the same may be any other suitable source of program material, such as AM and FM radio receivers. It is, of course, assumed that the audio output from the two sources of program material is in accordance with standard stereophonic sound recording principles.

The system shown in Fig. 1 also incorporates a full frequency range loudspeaker 10 which may be of the direct radiator cone type or any other suitable type of loudspeaker having a wide range frequency response, but it is imperative that this loudspeaker 10 be provided with two separate voice coils 11 and 12. It has been found that the use of two separate voice coils provides superior performance in that, there is no possibility of coupling or interaction between the two amplifiers or other program sources connected thereto which conceivably could cause instability and distortion.

Voice coil 11 is connected through suitable conductors 13 with the amplifier A or other source of program material and a volume level control 14 is provided in order to limit the input to the voice coil 11 from the amplifier A. Connected in this manner, the loudspeaker 10 will reproduce the full frequency output of the amplifier A and it is, of course, understood that by full frequency output is meant the full range of frequencies which the particular equipment is capable of providing and reproducing.

The second voice coil 12 is connected through suitable conductors 15 with a low-pass filter 16 which in turn is connected through suitable conductors 17 with the output of amplifier B. It will, therefore, be seen that in addition to reproducing the full frequency output of amplifier A, loudspeaker 10 will also serve to reproduce only the low frequency output of amplifier B.

A middle and high frequency range loudspeaker 18 is provided with a voice coil 19 which is connected through suitable conductors 20 to a high-pass filter 21 which in turn is connected through suitable conductors 22 to the output of amplifier B. Provided in the connection between voice coil 19 and high-pass filter 21 is a volume level control 23. While the loudspeaker 18 has been referred to as a middle and high frequency range loudspeaker, it is, of course, understood that this can constitute a single loudspeaker or may be a plurality of speakers in which one is designed to reproduce the middle

frequencies while the other is designed to reproduce only the high frequencies. However, a single speaker will normally provide satisfactory reproduction of both the middle and high frequency output.

In operation of the system shown in Fig. 1, it is, of course, understood that the loudspeakers 10 and 18 will be mounted in suitable speaker enclosures or baffles and that they will be located at appropriate distances apart in the particular room where utilized in order to provide proper distribution of the sound emanating therefrom. Since all of the low frequency output from both amplifiers A and B is reproduced by the loudspeaker 10, no directional characteristics of such low frequencies will be evident to the listener, but since this loudspeaker 10 reproduces middle and high frequency output of amplifier A it is important that loudspeaker 10 be located in such a position that the middle and high frequencies will be directed to the proper point in the listening area for maximum listening enjoyment. It is to be noted that middle and high frequency sound waves are highly directive and consequently placement of both of the speakers with due regard for the proper distribution of such middle and high frequency sound waves is important.

Since the loudspeaker 18 reproduces only the middle and high frequency output of amplifier B, this loudspeaker will, of course, be located in such a manner as to direct the sound emanating therefrom to an appropriate point in the listening area and since the loudspeakers 10 and 18 are located at spaced points, a stereophonic effect will result. The volume level controls 14 and 23 are provided in order to permit adjustment of the output from the two amplifiers to the two loudspeakers in order to balance the sound emanating therefrom whereby substantially true and life-like sound reproductions will result.

It will thus be seen that by the above described form of the invention there has been provided a relatively simple stereophonic sound propagation system utilizing a minimum number of loudspeakers and at the same time providing for proper sound propagation and for proper balance of the output level of the two loudspeakers.

A modified form of the invention is shown in Fig. 2 which may well comprise two sources of program material, such as amplifier A and amplifier B, and there is also provided a loudspeaker 24 which has low frequency range response, having separate voice coils 25 and 26. Alternatively, its response may be restricted to low frequencies. Unless it is so restricted, voice coil 25 is connected to a low-pass filter 27 which in turn is connected through suitable conductors 28 to the output of amplifier A. Voice coil 26 is connected to a low-pass filter 29 which in turn is connected through suitable conductors 30 to the output of amplifier B. If the loudspeaker range is restricted to low frequencies, the low-pass filters are not required to be so effectual and may even be omitted in some cases.

A middle and high frequency range loudspeaker 31 is provided with a voice coil 32 which is connected to a high-pass filter 33 which in turn is connected through suitable conductors 34 to the output of amplifier A between such amplifier and the low-pass filter 27. Connected between the high-pass filter 33 and voice coil 32 is a volume level control 35. Consequently, it will be seen that loudspeaker 31 operates to reproduce only the middle and high frequency output of amplifier A.

Loudspeaker 31 is disposed at one side of the low frequency loudspeaker 24 in spaced relation thereto and disposed on the opposite side in spaced relation to the low frequency speaker 24 is a second middle and high frequency range loudspeaker 36 having a voice coil 37 connected to a high-pass filter 38 which in turn is connected through suitable conductors 39 to the output of amplifier B between the low-pass filter 29 and the amplifier B. Connected between the high-pass filter 38 and

voice coil 37 is a volume level control 40. It will thus be seen that loudspeaker 36 operates to reproduce only the middle and high frequency output of amplifier B.

In the operation of the stereophonic sound propagation system shown in Fig. 2 and described above, the low frequency loudspeaker 24 reproduces the low frequency output from both amplifier A and amplifier B and since such low frequency output is non-directional as explained above, loudspeaker 24 may be positioned at any desired location in the room or other listening location. The loudspeakers 31 and 36, however, must be positioned in such a manner that the middle and high frequency sound waves emanating therefrom will be directed to proper points in the listening area, since such sound waves are highly directive and the listening audience will immediately sense the direction or point from which such sound waves emanate. The system shown in Fig. 2 is primarily designed to be utilized in relatively large listening areas since the loudspeaker 24 will operate to fill in the center of the listening area with sound, whereas the system shown in Fig. 1 would, in all probability, operate more satisfactorily in a smaller listening area. Obviously, the relative output of the two loudspeakers 31 and 36 may be adjusted by the volume level controls 35 and 40 and where properly placed in a listening area, this system will operate to provide true stereophonic sound propagation.

The further modified form of the invention shown in Fig. 3 is also primarily designed to be utilized in larger listening areas and in this system as in common with the other systems described above, there may be provided two sources of program material, such as amplifiers A and B. In this system a centrally located full frequency range loudspeaker 41 is utilized and such speaker is provided with two separate voice coils 42 and 43. Voice coil 42 is connected to the output of amplifier A through suitable conductors 44, while voice coil 43 is connected to the output of amplifier B through suitable conductors 45. Consequently, such loudspeaker 41 will operate to reproduce the full frequency output of both amplifiers A and B.

A middle and high frequency range loudspeaker 46 is provided with a voice coil 47 which is connected to a high-pass filter 48 which is connected through suitable conductors 49 to the output of amplifier A. Thus it will be seen that the speaker 46 operates only the middle and high frequency output from amplifier A. A volume level control 50 may be provided in the connection between the voice coil 47 and the high-pass filter 48 in order to control the output of speaker 46.

A second middle and high frequency range loudspeaker 51 is provided with a voice coil 52 connected to a high-pass filter 53 which in turn is connected through suitable conductors 54 to the output of amplifier B. A volume level control 55 may be provided in the connection between the voice coil 52 and the high-pass filter 53 in order to control the output of speaker 51. Consequently, it will be seen that speaker 51 operates to reproduce only the middle and high frequency output of amplifier B.

As stated above, the system shown in Fig. 3 is well suited to use in relatively large listening areas in that, the full range loudspeaker 41 operates to reproduce the full frequency output of both amplifiers and consequently adequately fills in the center portion of the listening area. The stereophonic effect is provided by the two middle and high frequency range loudspeakers disposed on opposite sides of the speaker 41 and this system occupies a relatively small space, since it is only necessary to provide a relatively large enclosure for the full range speaker 41, whereas the other speakers 46 and 51 may be disposed in relatively small enclosures which may be conveniently located at any desired point. Once again, in this system the provision of two separate voice coils on the central common speaker 41 operates to completely isolate the amplifiers A and B thereby eliminating any

possibility of coupling or interaction which might cause instability and distortion. The output from speakers 46 and 51 may be regulated by the volume level controls 50 and 55 in order to properly balance the sound output for the particular listening location in which the system is installed. The above described systems all utilize at least one loudspeaker having separate voice coils and various combinations of other middle and high frequency range loudspeakers may be utilized to provide the stereophonic effect and the proper sound distribution to the listening area. This arrangement eliminates the necessity of providing extremely large loudspeaker enclosures which is necessary in a system utilizing a plurality of full range loudspeakers or loudspeakers arrays and consequently, installation problems and furniture arrangements in listening areas, particularly in the home, are materially reduced.

A further advantage of the double voice coil feature described above is the substantially complete suppression of hum caused by turntable motor vibrations. With the use of two-element phonograph pickups hum caused by motor vibrations may be objectionable and connection of the two output channels to the two voice coils in the proper phase relationship serves to balance out the hum output resulting in signals having minimum hum content.

It will be obvious to those skilled in the art that various changes may be made in the invention without departing from the spirit and scope thereof and therefore the invention is not limited by that which is shown in the drawing and described in the specification, but only as indicated in the appended claims.

What is claimed is:

1. A stereophonic sound propagation system comprising two sources of program material, a full frequency range loudspeaker having two separate voice coils, one voice coil being connected to the first source for reproducing substantially the full frequency output of said first source, the other voice coil being connected to the second source through a low-pass filter for reproducing only the low frequency output of said second source and a middle and high frequency range loudspeaker adapted to be disposed in spaced relation on one side of said first speaker, said middle and high frequency speaker being connected to said second source through a high-pass filter to reproduce only the middle and high frequency output of said second source.
2. A system as defined in claim 1 in which a volume level control is provided in the connection to said one voice coil of said first speaker and a second volume level control is provided between said high-pass filter and said second speaker.
3. A stereophonic sound propagation system comprising two sources of program material, a full frequency range loudspeaker having two separate voice coils, one voice coil being connected to the first source for reproducing substantially the full frequency output of said first source, the other voice coil being connected to the second source through a filter for reproducing only the low frequency output of said second source and a second loudspeaker disposed in spaced relation to one side of said first speaker, said second speaker being connected to said second source through a filter to reproduce only the middle and high frequency output of said second source.
4. A stereophonic sound propagation system comprising two sources of program material, a loudspeaker having two separate voice coils, one voice coil being connected to the first source for reproducing the output of said first source, the other voice coil being connected to the second source through a filter for reproducing only the low frequency output of said second source and a second loudspeaker disposed in spaced relation to one side of said first speaker, said second speaker being connected to said second source through a filter to re-

produce only the middle and high frequency output of said second source.

5. A stereophonic sound propagation system comprising two sources of program material, a low frequency range loudspeaker having two separate voice coils, one voice coil being connected to the first source through a low-pass filter to reproduce only the low frequency output of said first source, the other voice coil being connected to the second source through a second low-pass filter to reproduce only the low frequency output of said second source, a first middle and high frequency range loudspeaker adapted to be disposed on one side of said first speaker, said middle and high frequency speaker being connected through a high-pass filter to said first source between said first low-pass filter and said first source to reproduce only the middle and high frequency output of said first source and a second middle and high frequency range loudspeaker disposed in spaced relation to said first, middle, and high frequency range, said second middle and high frequency speaker being connected through a second high-pass filter to said second source between said second low-pass filter and said second source to reproduce only the middle and high frequency output of said second source.

6. A system as defined in claim 5 in which a volume level control is provided in the connection between each high-pass filter and each middle and high frequency range speaker.

7. A stereophonic sound propagation system comprising two sources of program material, a low frequency range loudspeaker having two separate voice coils, one voice coil being connected to the first source through a filter to reproduce only the low frequency output of said first source, the other voice coil being connected to the second source through a second filter to reproduce only the low frequency output of said second source, a middle and high frequency range loudspeaker adapted to be disposed in spaced relation to said low frequency speaker on one side, said middle and high frequency speaker being connected through a filter to said first source between said first filter and said first source to reproduce only the middle and high frequency output of said first source and a second middle and high frequency range loudspeaker disposed in spaced relation to said low frequency speaker on the opposite side, said second middle and high frequency speaker being connected through a filter to said second source between said second filter and said second source to reproduce only the middle and high frequency output of said second source.

8. A stereophonic sound propagation system comprising two sources of program material, a loudspeaker having two separate voice coils, one voice coil being connected to the first source through a filter to reproduce only the low frequency output of said first source, the other voice coil being connected to the second source through a second filter to reproduce only the low frequency output of said second source, a second loudspeaker disposed in spaced relation to said first speaker on one side, said second speaker being connected through a filter to said first source between said first filter and said first source to reproduce only the middle and high frequency output of said first source and a third speaker disposed in spaced relation to said first speaker on the opposite side, said third speaker being connected through a filter to said second source between said second filter and said second source to reproduce only the middle and high frequency output of said second source.

9. A stereophonic sound propagation system comprising two sources of program material, a full frequency range loudspeaker having two separate voice coils, one voice coil being connected to the first source for reproducing substantially the full frequency output of said first source, the other voice coil being connected to the second source for reproducing substantially the full frequency output of said second source, a middle and high frequency range

loudspeaker disposed in spaced relation to said full range speaker on one side, said middle and high frequency speaker being connected to a high-pass filter to said first source to reproduce only the middle and high frequency output of said source and a second middle and high frequency range loudspeaker disposed in spaced relation to said full range speaker on the opposite side, said second middle and high frequency speaker being connected through a second high-pass filter to said second source to reproduce only the middle and high frequency output of said second source.

10. A system as defined in claim 9 in which a volume level control is provided in the connection between each high-pass filter and each middle and high frequency range speaker.

11. A stereophonic sound propagation system comprising two sources of program material, a full frequency range loudspeaker having two separate voice coils, one voice coil being connected to the first source for reproducing substantially the full frequency output of said first source, the other voice coil being connected to the second source for reproducing substantially the full frequency output of said second source, a middle and high frequency range loudspeaker adapted to be disposed in spaced relation to said full range speaker on one side, said middle and high frequency speaker being connected through a filter to said first source to reproduce only the middle and high frequency output of said first source and a second middle and high frequency range loudspeaker adapted to be disposed in spaced relation to said full range speaker on the opposite side, said second middle and high frequency speaker being connected through a second filter to said second source to reproduce only the middle and high frequency output of said second source.

12. A stereophonic sound propagation system comprising two sources of program material, a loudspeaker having two separate voice coils, one voice coil being connected to the first source, the other voice coil being connected to the second source, a second loudspeaker disposed in spaced relation to said first speaker on one side, said second speaker being connected through a filter to said first source to reproduce only the middle and high frequency output of said first source and a third loudspeaker disposed in spaced relation to said first speaker on the opposite side, said third speaker being connected through a second filter to said second source to reproduce only the middle and high frequency output of said second source.

13. A stereophonic sound propagation system comprising two sources of program material, a loudspeaker having two separate voice coils, one voice coil being connected to the first source, the other voice coil being connected to the second source, a second loudspeaker adapted to be disposed in spaced relation to said first speaker on one side, said second speaker being connected to said first source, and a third loudspeaker adapted to be disposed in spaced relation to said first speaker on the opposite side, said third speaker being connected to said second source.

14. A stereophonic sound propagation system comprising two sources of program material, a loudspeaker having two separate voice coils, one voice coil being connected to one source and the other voice coil being connected to the second source and at least one middle and high frequency range loudspeaker disposed in spaced relation to one side of said first named speaker, said middle and high frequency speaker being connected to either source through a high-pass filter to reproduce only the middle and high frequency output of said source.

15. A system as defined in claim 14 in which a volume level control is provided between said high-pass filter and said middle and high frequency speaker.

16. A stereophonic sound propagation system comprising two sources of program material, a loudspeaker having two separate voice coils, one voice coil being con-

nected to one source and the other voice coil being connected to the second source and at least one loudspeaker adapted to be disposed in spaced relation to one side of said first named speaker, said second speaker being connected to either source through a high-pass filter to reproduce only the middle and high frequency output of said source.

17. A stereophonic sound propagation system comprising two sources of program material, a loudspeaker having two separate voice coils, one voice coil being connected to one source and the other voice coil being connected to the second source and at least one loudspeaker disposed in spaced relation to one side of said first named speaker, said second speaker being connected to either source.

18. A stereophonic sound propagation system comprising two sources of program material, a loudspeaker having at least low frequency range response and having

two separate voice coils, a middle and high frequency range loudspeaker adapted to be disposed in lateral spaced relationship to said first loudspeaker, one voice coil of said first loudspeaker being connected to one source, the other voice coil of said first loudspeaker and said second loudspeaker being connected to the other source and means for limiting the reproduction of middle and high frequency range output of said other source by said other voice coil of said first loudspeaker.

19. A stereophonic sound propagation system as defined in claim 18 in which the means for limiting the reproduction of middle and high frequency range output by said other voice coil comprises a low-pass filter connected between said other source and said other voice coil.
